UNITED STATES PATENT OFFICE.

EDWARD C. SOFIO, OF HOBOKEN, AND LINDSLEY SCHEPMORE, OF HASBROUCK HEIGHTS, NEW JERSEY, ASSIGNEES TO SAFETY CAR HEATING & LIGHTING COMPANY, A CORPORATION OF NEW JERSEY.

LIGHTING-FIXTURE.

1,117,270.

Specification of Letters Patent. Patented Nov. 17, 1914.

Application filed June 14, 1911. Serial No. 633,137.

To all whom it may concern:

Be it known that we, EDWARD C. SOFIO, a citizen of the United States, residing in Hoboken, county of Hudson, and State of New Jersey, and LINDSLEY SCHEPMORE, a citizen of the United States, residing in Hasbrouck Heights, county of Bergen, and State of New Jersey, have invented new and useful Improvements in Lighting-Fixtures, 10 of which the following is a description.

Our invention pertains to that class of lighting fixtures adapted to adjustably hold an incandescent lamp in a fixed position in such manner that its position may readily 15 be altered as will hereinafter more plainly appear.

Figure 1 of the drawing is a vertical section of one form of lighting fixture embodying our invention. Fig. 2 is a vertical plan 20 of the fixture shown in Fig. 1. Fig. 3 is an elevation of a portion of the fixture shown in Fig. 1. Fig. 4 is a partial vertical section showing in elevation some of the parts shown in section in Fig. 1.

25 Referring to the drawings, particularly Fig. 1, 1 represents a base plate which may be attached to the member indicated at 2 upon which the fixture is supported and held in place as by screws 3. The base plate 1 is provided with the extension 4 which is preferably threaded and carries the sleeve 5 provided with the opening 6 through which the wires 7 may be led into the fixture. The extension 4 is provided on its 30 upper horizontal face with radial teeth 8 as shown particularly in Fig. 4 and indicated by dotted lines in Fig. 1. The sleeve 9, having the bore 10, is fitted snugly over the sleeve 5 and provided at its lower end with 35 the flange 11, also having radial teeth engaging the teeth 8 and pressed downwardly thereupon as by means of the spring 12 carried within the sleeve nut 13 threaded upon the member 4 and provided with the flange 40 portion 14 for engaging the said spring. The sleeve 9 has attached thereto the revolvable petticoat 15 carrying the vertical hollow member 16 provided with an arm 17 having the corrugated head 18 upon which is fastened the bifurcated member 20 (see Figs. 1, 45 2 and 3) as by screws 19. The member 20 is provided with an extension 21 carrying the round nosed bolt 22 normally pressed into engagement with the member 18 as by the

spring 23. The member 20 also has the 55 threaded portion 24 upon which is threaded the nipple 25 carrying the spring shade engaging means 26 which may be pressed into engagement with the shade 28 as by the conical bonnet 27 threaded upon said nipple 60 above said engaging means.

29 is the lamp socket carried by the nipple 25 and adapted to carry the bulb 30. 29 is properly connected in an obvious manner with any external circuit as by means of 65 wires 7.

The operation of our improved fixture is substantially as follows: With the base plate 1 fixed rigidly in position as shown in Fig. 1 and the teeth 11 and 8 pressed into engagement by the spring 13 as shown, the member 16 carrying the lamp cannot revolve unless sufficient force be applied thereto to cause the sleeve 9 to be raised against the spring 13 and the teeth moved into different relative engagement and thus the lamp is yieldingly locked in any position into which it may be revolved as, for example, when the center line of the arm 17 indicated at a—b in Fig. 2 is swung into the position a—c in 80 said figure. If it be desired to change the angular position of the lamp 30 this may readily be accomplished by applying sufficient force in the direction desired to move the lamp to cause the spring bolt 22 to rise 85 over one of the corrugations of the member 18 and fall into the next hollow and so on until the proper position is reached as, for example, that indicated by dotted lines in Fig. 1. Thus it will be seen that the lamp 90 together with its shade holder and holding means and other such parts are yieldingly locked in fixed positions as may be desired.

From the foregoing it will be plain that our improved lighting fixture is particularly 95 applicable to cars and other uses where the same is liable to be subjected to considerable vibration and that when used under such conditions, it will remain in the fixed position into which it may readily be forced 100 without suffering alteration due to vibration.

We do not wish in any way to limit ourselves to the exact details of construction nor to the exact mode of operation set forth in this specification and drawing which are 105 given as one example of lighting fixture embodying the essentials of our invention, for it is obvious that wide departure in both

may be made without departing from the spirit and scope of our invention which is as set forth in the following claims, to wit:

1. A lighting fixture comprehending a rigid supporting member; means permitting the same to be moved to a lateral position and for yieldingly locking the same in such position; means for carrying a source of illumination comprising a movable member mounted on said supporting member by means permitting it to be moved at a right-angle to the movements of the supporting member; and means for yieldingly locking the carrying means in fixed relations with respect to the supporting member.
2. A lighting fixture comprehending a base member; an extension member carried thereby; a supporting member; means for revolubly connecting said supporting member with the extension member; means for yieldingly holding the supporting member in definite positions of revolution; a member carried by said supporting member provided with engaging means; and means for carrying a source of illumination movably mounted upon said member and provided with yielding means coöperating with said engaging means.
3. A lighting fixture comprehending a base member adapted to be held in a fixed position; a projecting member carried thereby; a carrying member carried upon said projecting member and revoluble thereupon; yielding means for opposing said revolution.

and for holding the carrying members in adjusted position; a swinging member supported by said carrying member; a source of illumination carried by said swinging member; and yielding means opposing the motion of said swinging member.

4. A lighting fixture comprehending a base member adapted to be held in a fixed position; a standard revolubly mounted thereupon; yielding means for opposing the revolution of said standard and for holding it in adjusted position; lamp carrying means supported by said standard in movable relation thereto; and yielding locking means opposing the motion of said lamp carrying means, and for holding the latter in adjusted position.

5. A lighting fixture comprising a base; a hollow member or support revolubly mounted upon said base; means between the base and support for yieldingly holding the two in adjusted position; and for permitting the two to be moved for adjustment by force applied to one of them; an arm extending from the support, and means carried by said arm for adjustably holding a lighting fixture in various positions relatively to the arm.
